UNITED STATES PATENT OFFICE.

JOSEPH N. MAHONEY, OF BROOKLYN, NEW YORK, ASSIGNOR TO WESTINGHOUSE ELECTRIC & MANUFACTURING COMPANY, A CORPORATION OF PENNSYLVANIA.

CIRCUIT INTERRUPTER.

Original application filed December 8, 1917, Serial No. 206,131. Divided and this application filed November 30, 1920. Serial No. 427,308.

This application is a division of application, Serial No. 206,131, filed Dec. 8, 1917.

My invention relates to circuit interrupters and particularly to circuit interrupters of the quick-acting type such as that shown and described in my Patent No. 1,431,970, granted Oct. 17, 1922, of which this application is a division.

The object of my invention is to provide a circuit interrupter that shall have contact members of such shape and construction and that shall be so provided with arc dissipating means between stationary contact members thereof as to permit the same to be placed relatively close together, thereby permitting the interrupter to be more economically and compactly constructed and of improved operating characteristics.

Heretofore, it has been usual to provide certain types of circuit interrupters with spaced stationary contact members and a bridging contact member therebetween. These interrupters have usually required that the stationary contact members be placed a relatively great distance apart to prevent the formation of arcs therebetween and, as a result, have been unnecessarily bulky and expensive.

In practicing my invention, I provide laminated stationary contact members and arc-ing horn members of such form and relation to a rigid bridging contact member as to permit the latter to be of substantially minimum length.

The single figure of the accompanying drawings is a front elevational view of the circuit interrupter embodying my invention.

A circuit interrupter 1 comprises, in general, a supporting member or frame 2, stationary main contact members 3, combination horn-gap and auxiliary stationary arc-ing contact members 4, a slid-able multi-part rod structure 5 having a main bridging contact member 6 and an auxiliary bridging contact member 7 mounted at the upper end thereof and a toggle or operating mechanism 8 disposed between the lower end of the rod structure 5 and a stationary pin 9. An electromagnet 10 is adapted to be energized for the purpose of upsetting the toggle mechanism 8 to trip the interrupter 1.

Terminal members or studs 11, that are suitably spaced with respect to each other and disposed at substantially right angles to

the stationary contact members 3, project from the rear of the frame structure 2 for co-operation with conducting leads (not shown).

The main stationary contact members 3, preferably constructed of laminated material, extend, and are curved downwardly, toward each other so that their inner ends are disposed relatively close together in substantially the same horizontal plane. Blocks 12, of copper or other conducting material, are secured to the ends of the studs 11 and are provided with forwardly extending curved seat portions 13 for the reception of the outer ends of the stationary contact members 3. Screws 14 secure the members 3 between the seat portions 13 and movable clamping blocks 15 having upper surfaces 16 conforming to the members 3.

The combination horn-gap and auxiliary stationary arc-ing contact members 4 comprise upwardly diverging horn portions 17 having auxiliary contact portions 18 at their lower ends and rear portions 19 through which screws 20 extend to secure the same to the blocks 12. Elongated members 21 are disposed substantially radially with respect to the auxiliary contact members 7 between the members 4 to prevent the arc, incident to the opening of the interrupter, from bowing outwardly too far from the interrupter.

The rod structure 5 comprises a lower rod 22 and an upper exteriorly-threaded sleeve 23 that are, respectively, mounted in insulating blocks 24 and 25 joined by screws 26. An insulating plate 27 is disposed between the blocks 24 and 25. This arrangement effectually insulates the contact members from the operating mechanism.

The main bridging contact member 6 is of substantially inverted U-shape having end portions 28 for engagement with the main stationary contact members 3 and an interiorly-threaded center recessed portion by which it is mounted on the upper end of the sleeve 23.

A pin 29 secures the auxiliary bridging contact member 7 to the upper end of a plunger 30 disposed in the sleeve 23 in the lower portion of which a compression spring 31 extends between the inner end of the plunger 30 and the plate 27. A pin 32 extends through the main bridging contact member 6, through the sleeve 23 and through

a longitudinal slot 34 in the plunger 30. A nut 33 is provided to lock the sleeve 23 in position with respect to the block 25. The arrangement whereby the pin 32 extends through the main bridging contact member 6, the sleeve 23 and the slot 33 prevents the angular displacement of the member 6 about the rod structure 5 and permits the outward movement of the plunger 30 with respect to the sleeve 23.

In operation, when the toggle mechanism 8 is upset, the rod structure 5 moves quickly downward to separate the main bridging contact member 6 from the main stationary contact members 3. By reason of the lost-motion arrangement of the auxiliary bridging contact member 7 with respect to the main bridging member 6, the member 7 will remain in contact with the auxiliary contact portions 18 until the main bridging member 6 is somewhat removed from the main stationary contact members 3, after which the circuit will be broken at the auxiliary contact members and any arc formed will be dissipated along the horn portions 17.

An interrupter constructed in accordance with my invention provides good contact between the contact members, is very compact and, therefore, economical to manufacture.

While I have shown and described a particular form of my invention, changes may be effected therein without departing from

the spirit and scope thereof, as set forth in 35 the appended claims.

I claim as my invention:—

1. A circuit interrupter comprising a pair of spaced leaf-spring stationary contact members disposed in substantially inverse 40 flaring relation, a movable bridging contact member for engagement with the adjacent ends thereof, a pair of horn-gap members each having a contact portion disposed between the stationary contact members and being connected in paired relation to one of the latter, and an auxiliary contact member for co-operation with said contact portions.

2. A contact member for an electrical device comprising a base member, clamping bolts secured thereto, clamping blocks provided with co-operating curved surfaces secured by said bolts, and a laminated contact brush secured between said blocks.

3. A contact member for an electrical device comprising a base member, clamping bolts secured thereto, clamping blocks provided with co-operating curved surfaces secured by said bolts, a laminated contact brush secured between said blocks, and an auxiliary contact member secured to one of said blocks and terminating adjacent to the free end of said brush.

In testimony whereof, I have hereunto subscribed my name this 23 day of November, 1920.

JOSEPH N. MAHONEY.
